213,440

SOLVENT DISPENSER FOR A WATER SOFTENING SYSTEM OR THE LIKE

Leo F. Wildgen, Hennepin County, Minn., assignor, by
mesne assignments, to Union Tank Car Company, a
corporation of Delaware

Filed July 18, 1966, Ser. No. 3,108

Term of patent 14 years

U.S. Cl. D23—3
Int. Cl. D23—01

FIG. 1 is a front elevational view of a solvent dispenser for a water softening system or the like showing my new design,

FIG. 2 is a side elevational view thereof, and

FIG. 3 is a top plan view thereof.

I claim:

The ornamental design for a solvent dispenser for a water softening system or the like, as shown.
